WINDOW FASTENER

Bert A. Quinn, St. Paul Park, Minn.

Application April 20, 1942, Serial No. 439,623

15 Claims. (CL. 292—265)

My invention relates to an improvement in window fasteners, wherein it is desired to provide a simple and efficient type of fastener for supporting a pivoted window in adjusted relation with respect to its frame.

The object of the present invention is to avoid previously encountered difficulties in the formation of fasteners of this general type. With my construction, I desire to avoid the necessity of locking the bracket arms when the window is closed. I also desire to provide a construction which will not rattle when the window is open to an adjusted position.

An object of the present invention lies in the provision of bracket arms which are angularly-shaped in cross-section. This construction stiffens the arms and prevents injury to the arms due to the bending of the arms in use. This construction also serves to maintain the arms in proper relation to the brackets, as with this construction the arms can not readily be bent out of shape.

It is a further object of my invention to provide a bracket over which the bracket arm may pivot and which is so arranged with respect to the pivot connecting the bracket arm to the window that an outward pull on the window will not tend to pivot the bracket arm. With this arrangement the bracket arms may be pivoted into vertical position without danger of having an outward force upon the window swing the arms into horizontal position so that the window may open. Thus, when the bracket arms are folded down into substantially parallel relation with the closed window, the window is locked from outward movement.

A further feature of the present invention lies in the provision of a wedge-shaped receiving element on the bracket for receiving the bracket arm. When the bracket arm is engaged in this wedge-shaped notch, the arm is firmly held by the bracket and the bracket arm can not rattle with respect to the bracket.

These and other objects and novel features of my invention will be more clearly and fully set forth in the following specification and claims.

In the drawing forming a part of my specification:

Figure 1 is a perspective view of my window fastener in operation.

Figure 2 is a side elevation view of the window fastener in closed position thereof.

Figure 3 is an elevation view of the bracket or stile plate secured to the window frame, showing in cross-section the relation of the bracket arm engaged thereto.

Figure 4 is a view similar to Figure 3 showing the position of the bracket arm with respect to the bracket when the window is being opened or closed.

Figure 5 is a side elevation view of the bracket or stile plate showing the relation of the bracket arm with respect thereto.

The storm window fastener A includes a bracket arm B, which is pivotally secured to the window C. As will be clearly understood the fastener A is adaptable for various purposes, but is usually used for holding a storm window or the like in adjusted relation with respect to the window frame.

The bracket arm, indicated in general by the letter B, comprises an elongated arm 10, which is preferably right angular in cross-sectional shape, and which includes a substantially vertical flange 11 which extends on a substantially vertical plane, and a right angularly extending flange 12. In the form illustrated, the flange 11 terminates at the extreme free end of the arm 10, and the flange 12 continues to form a turned-down handle end 13, by means of which the position of the bracket arm may be regulated.

An attaching plate 14 is provided on the storm window C, which is secured to the storm window by means of attaching screws 15, or the like. The attaching plate or bracket 14 is right angular in cross-section and it includes a flange 16 designed to overlie the surface of the window C and through which the screws 15 extend, and a second flange 17 extending substantially normal to the surface of the window C. The right angular arm 10 is pivotally attached to the attaching bracket 14 by means of a pivot 19 which extends through the flange 17 and through the vertical flange 11 of the angular arm 10.

The stile plate or bracket plate D comprises a base 20 designed to lie flush against the surface of the window frame E, and attaching bolts 21, or other suitable fastening means extend through the plate 20 to attach this bracket plate to the window frame. A flange 22 extends outwardly from the plate 20 at substantially right angles with respect thereto, and this plate 22 is preferably arranged angularly with respect to the vertical edges of the base 20. In other words, the flange 22 is preferably arranged so that when the window bracket arm B is holding the window in open position, the arm will extend at substantially right angles with respect to the flange 22.

The flange 22 includes a substantially V-shaped or wedge-shaped slot 23 which is designed to receive the bracket arm B. The upper extremity 24 of the flange 22 is positioned substantially in horizontal alignment with the pivot 19 in closed position of the window, as best illustrated in Figure 2 of the drawing. As a result the window may be locked in closed position, as will be later described in detail.

The angularly extending flange 12 of the angular arm 10 is provided with a series of spaced slots 25. These slots 25 are of a width to re-

ceive the flange 22, as best illustrated in Figure 1 of the drawing. The upper end of the flange 22 is slightly wider than the portion of this flange adjacent the slot 23 in order to hold the bracket arm in slidable relation with the bracket, as will be later described.

In operation, the angular arm 10 normally rests upon the upper extremity 24 of the flange 22, as illustrated in dotted outline in Figure 5 of the drawing, and as illustrated in full outline in Figure 4 of the drawing. As will be noted from an examination of Figure 4 of the drawing, the notches 25 do not extend the full width of the flange 12, so that the bracket arm may be slid along the upper extremity 24 of the bracket flange 22. In other words, as the window C is swung into open or closed position, the bracket arm 10 does not have a tendency to engage the flange 22 of the stile or bracket plate 20, as the flange 12 of the bracket arm will be supported upon the upper extremity 24. When it is desired to support the window in open position, the window is swung to the desired open position and the free end 13 of this arm is then drawn inwardly toward the center of the window frame a short distance. The flange 22 will then engage in a notch 25, as illustrated in dotted outline in Figure 4 of the drawing, and the bracket arm 10 may be swung downwardly into the receiving notch 23.

When the bracket arm 10 is moved into the position illustrated in dotted outline in Figure 4 of the drawing, the transverse pressure on the end of the arm may be released and the downward pivoting of the arm may continue. As the arm 10 pivots downwardly, the notch 25, embracing the flange 22, remains in engagement with the flange.

Downward movement of the bracket arm from the position illustrated in dotted outline in Figure 4 allows the arm to swing outwardly into its normal relation, this downward movement being continued until the vertical flange 11 engages the outer surface 26 of the notch 23. The V-shape or wedge-shape of the notch 23 causes the arm to be wedged into locked position, this wedging action acting to clamp the bracket arm in the notch and to thereby prevent any relative movement between the bracket arm and the bracket or stile plate.

When it is desired to pivot the window to a further open position, or to a closed position the end 13 of the bracket arm is raised. This raising of the bracket arm causes the arm to be sprung inwardly, the arm passing from the position illustrated in Figure 3 through the position illustrated in dotted outline in Figure 4, to the position illustrated in full lines in this figure. The flange 12 is then resting upon the upper extremity 24 of the flange 22 of the bracket or stile plate D, allowing pivotal movement of the window C.

In closing the window C, the window is pulled inwardly by the bracket arm until the attaching bracket 14 comes into overlapping relation with the stile or bracket plate D. The position of the bracket plate D is so related to the closed position of the attaching plate 14 that the pivot 19 will be just outwardly of the upper extremity 24 of the flange 22. As a result the downward movement of the angular arm 10 will cause the flange 12 to engage over the flange 22, and if any force against the window C, tending to open the window, is exerted through the bracket 14 and the bracket arm 10, directly against the flange 22, the outward movement is blocked by the flange

22. Furthermore, as the upper edge of the flange 22 is substantially opposite to the pivot 19, there is little or no tendency for the bracket arm to pivot when such an outward force on the window 5 is exerted. As a result no separate locking means is required and it is not necessary that the bracket arm be held by some additional means in substantially vertical position in parallel relation to the window C in order that the window be locked in closed position.

In accordance with the patent statutes, I have described the principles of construction and operation of my window fastener, and while I have endeavored to set forth the best embodiment 15 thereof, I desire to have it understood that obvious changes may be made within the scope of the following claims, without departing from the spirit of my invention.

I claim:

20. 1. A fastener for a pivoted element in a frame, the fastener including an arm pivotally secured to said pivoted element, said arm being substantially right angular in cross-section, a bracket secured to said frame, a flange on said bracket 25 extending outwardly from said frame, a wedge-shaped recess in said flange designed to accommodate said arm, said arm having notches in one angular edge thereof engageable with said flange, said notches designed to embrace a portion of said flange adjacent said recess, the other angular edge of said arm on the side of the arm opposite the notch engaging the side of the recess opposite that embraced by said notch.

35. 2. A window fastener for a pivoted window in a frame, the fastener comprising an arm pivotally secured to the window, a bracket secured to the frame, an outwardly extending flange on said bracket, said flange having a wedge-shaped slot 40 therein, said flange terminating substantially inwardly of the pivotal connection between the arm and the window in closed position of the window, said arm being pivotal around said flange to lock said window closed, and said arm engageable in said slot in said flange to hold the arm in adjusted 45 relation with respect thereto.

50. 3. A window fastener for a pivoted window in a frame, the fastener comprising an arm pivotally secured to the window, a bracket secured to the frame, an outwardly extending flange on said bracket, said arm being angular in cross-section and embracing a corner of said flange, said flange terminating inwardly of the pivotal connection of said arm with said window in closed position of said window, said arm being pivotal downwardly 55 inwardly of said flange in closed position thereof to lock said window closed.

60. 4. A window fastener for a window pivotally mounted in a frame, the fastener comprising an arm angular in cross-section, a pivot extending substantially parallel to the pivots connecting said window to said frame, connecting said arm to said window, a bracket on said frame, a flange projecting outwardly from said frame on said bracket, said arm designed to embrace a corner 65 of said bracket, said flange terminating inwardly of said pivot connecting said arm to said window, said arm pivoting around said flange in closed position of said window to lock the window in closed position.

65. 5. A window fastener for a window pivotally supported in a frame, the fastener comprising an arm, a pivot connecting said arm to said window, said pivot extending substantially parallel to the pivots connecting the window to the frame, a bracket on said frame, said bracket including an

outwardly extending flange, said flange terminating at its upper end inwardly of said pivot in closed position of the window, said arm pivoting around said flange and engaging the inner surface thereof in closed position of the window to lock said window in closed position, a slot in said flange, and spaced notches in one edge of said arm designed to embrace the flange to allow said arm to extend into said notch.

6. A window fastener for a window pivotally supported in a frame, the fastener comprising an arm, a pivot connecting said arm to said window, said pivot extending substantially parallel to the pivots connecting the window to the frame, a bracket on said frame, said bracket including an outwardly extending flange, said flange terminating at its upper end inwardly of said pivot in closed position of the window, said arm pivoting around said flange and engaging the inner surface thereof in closed position of the window to lock said window in closed position, a slot in said flange, and spaced notches in one edge of said arm designed to embrace the flange to allow said arm to extend into said notch, said slot being shaped to wedge the arm in place when in said slot.

7. A window fastener for a window pivotally supported in a frame, the fastener comprising an arm, a pivot connecting said arm to said window, said pivot extending substantially parallel to the pivots connecting the window to the frame, a bracket on said frame, said bracket including an outwardly extending flange, said flange terminating at its upper end inwardly of said pivot in closed position of the window, said arm pivoting around said flange and engaging the inner surface thereof in closed position of the window to lock said window in closed position, a slot in said flange, and spaced notches in one edge of said arm designed to embrace the flange to allow said arm to extend into said notch, said slot being wedge-shaped to wedge said arm in adjusted position.

8. A window fastener for a window pivotally supported in a frame, the fastener comprising an arm, a pivot connecting said arm to said window, said pivot extending substantially parallel to the pivots connecting the window to the frame, a bracket on said frame, said bracket including an outwardly extending flange, said flange terminating at its upper end inwardly of said pivot in closed position of the window, said arm pivoting around said flange and engaging the inner surface thereof in closed position of the window to lock said window in closed position, a slot in said flange, and spaced notches in one edge of said arm designed to embrace the flange to allow said arm to extend into said notch, said flange being wider at its upper extremity than just below its upper extremity, so that said notches will not engage said flange unless said arm is moved in a direction away from said frame, and pivoted downwardly when a notch is in registry with said flange.

9. A window fastener comprising a bracket arm substantially right angular in cross-section, one right angular portion extending on a substantially vertical plane, spaced notches in the other right angular portion, a bracket secured to the window frame, a notch in said bracket, said spaced notches being engageable to embrace a portion of said bracket adjacent said notch in said bracket, and the edge of said one right angular portion

engaging the edge of the notch in said bracket opposite the edge thereof embraced by said spaced notches.

10. A window fastener comprising a bracket arm, means pivotally securing said bracket arm to the window, a bracket secured to the window frame and engageable with said arm, a notch in said bracket in which said arm may engage, and a cam shoulder on said bracket adjacent said notch, said cam shoulder holding said arm engaged in said notch unless said arm is sprung outwardly from the window frame by said cam shoulder.

11. A window fastener comprising an arm, means pivotally securing said arm to the window, a bracket secured to the window frame and engageable with said arm, a notch in said bracket engageable with said arm, a cam shoulder adjacent said notch, spaced notch means in said arm arranged to embrace a portion of said bracket adjacent said notch, said cam shoulder normally holding said arm in said notch, but guiding said arm out of said notch upon pivoting of said arm along said cam shoulder.

12. A window fastener comprising an arm substantially right angular in cross-section, means pivotally connecting said arm to the window, a bracket secured to the window frame including a notch engageable with said arm, spaced notch means in said arm designed to embrace a portion of the bracket adjacent said notch, a cam shoulder on said bracket adjacent said notch, said cam shoulder flexing said arm away from the adjacent window frame upon pivoting of the arm to withdraw said arm from said notch.

13. A window fastener comprising an arm substantially right angular in cross-section, means pivotally connecting said arm to the window, a bracket secured to the window frame including a notch engageable with said arm, spaced notch means in said arm designed to embrace a portion of the bracket adjacent said notch, a cam shoulder on said bracket adjacent said notch, said cam shoulder flexing said arm away from the adjacent window frame upon pivoting of the arm to withdraw said arm from said notch, one right angular portion of the arm being freely slidable along the top of said cam shoulder to open or close the window.

14. A window fastener for a pivoted window in a frame comprising an arm pivotally secured to said window, a bracket secured to the window frame, an outwardly extending flange on said bracket, said flange extending above the level of the pivot securing said arm to said window, said arm being slidable over said flange and pivoted around said flange when said window is in closed position, said arm depending downwardly from its pivotal attachment, said flange acting to lock said window in said closed position.

15. A fastener for a window pivotally supported in a window frame, the fastener comprising an arm pivotally secured to the window, pivot means connecting said arm and said window, a bracket on the window frame, a flange on said bracket extending away from said frame, said flange terminating at a point inwardly of the pivotal connection between the window and the arm in closed position of the window, said flange extending between a portion of said arm and said pivot means in closed position of the window to lock the window in closed position.

BERT A. QUINN.
